UNITED STATES PATENT OFFICE.

THOMAS M. JERVEY, OF WASHINGTON, DISTRICT OF COLUMBIA.

AUTOMATIC GUN.

Application filed October 15, 1923. Serial No. 668,643.

The subject of this invention is an automatic gun designed primarily for a caliber of 37 m/m or heavier, though not necessarily limited to any specific caliber.

5 In designing an automatic gun it is desirable that the loading of the gun should be positive and certain; that the parts may be operated manually as well as automatically; that jamming of rounds may be 10 quickly relieved; and that the structure should be as simple as proper functioning will permit.

With these and other objects in view I have devised a novel means for positioning 15 a charge to be loaded into the gun, associated with which is a novel rammer for forcing the charge home, the operation of the means for positioning the charge being such that jamming of the charge is easily and quickly 20 overcome, and the gun is designed with as few parts as is consistent with proper operation.

A practical embodiment of the invention is illustrated in the accompanying drawings, 25 wherein:

Fig. 1 is a right hand side elevation of the gun;

Fig. 2 is a left hand side elevation of the same;

30 Fig. 3 is a plan view with the magazine removed;

Fig. 4 is a rear elevation;

Fig. 5 is a rear elevation, partly in section, with the breech block shown open and 35 the parts in ready to load position;

Fig. 6 is a right hand side elevation, a portion of the cradle broken away, and the parts shown in the position assumed at the instant before the ramming home of the 40 charge;

Fig. 7 is a longitudinal sectional view showing the breech block closed and the feed tray in its up position;

Fig. 8 is a longitudinal sectional view of 45 the cradle with the gun removed and showing the feed tray in its up position.

Fig. 9 is a left hand side elevation, with a portion of the cradle broken away and parts in section, showing a round in the position assumed at the instant before ramming home the round;

Fig. 10 is a horizontal section, showing the parts in ready to fire position;

Fig. 11 is an enlarged fragmentary left 55 hand side elevation, with a portion in section;

Fig. 12 is a plan view of the forward feed tray arm;

Fig. 13 is an elevation of the same;

Fig. 14 is a plan view of the rear left hand feed tray arm;

Fig. 15 is an elevation of the same;

Fig. 16 is a plan view of the firing hammer;

Fig. 17 is an elevation of the same;

Fig. 18 is a plan view of the latch plate for retracting the cartridge release latch of the magazine;

Fig. 19 is a side elevation of the same;

Fig. 20 is a plan view of the cartridge release latch;

Fig. 21 is a side elevation of the same;

Fig. 22 is a view in elevation of the feed tray latch bolt;

Fig. 23 is an enlarged detailed sectional view of the hand operating slide;

Fig. 24 is a plan view of the same;

Fig. 25 is a view in elevation of the same;

Fig. 26 is a fragmentary sectional view of the magazine, showing the plungers for locking the magazine in place;

Fig. 27 is a similar view showing the mounting of the cartridge release pawl and the strip retaining means;

Fig. 28 is a fragmentary view in side elevation of the magazine;

Fig. 29 is a cross section of the rammer rod, showing the latch for locking the rod in its rearmost position;

Fig. 30 is a section of the rammer rod, 80 showing the cam groove and slot therein;

Fig. 31 is a sectional view showing the latch retaining bolt and latch plate assembly;

Fig. 32 is an enlarged detailed view, partly in section, of one of the cartridge retaining dogs;

Referring to the drawings by numerals of reference:

In carrying out my invention I provide a cradle 1 in which reciprocates the gun 2, 100 being guided in such reciprocation by ribs 3, provided on the gun near the breech thereof, working in guide ways 4 formed on the inner faces of the sides of the cradle (see Figs. 4 and 5).

A breech block 5 is provided for closing the breech of the gun, which, as herein shown, is of the vertically sliding type and is provided with a U-shaped recess 6 opening at its upper surface to permit a round to 110 be placed in and extracted from the gun when the breech is open. Arms 7 are pro-

vided on the breech block, the functions of which will appear as the description proceeds, and they may be conveniently provided by means of a yoke 8, with which they are integral, which is attached to the lower part of the breech block in any desired manner. As herein shown T ribs 9 are formed on opposed faces of the yoke adapted to enter T slots formed in the breech block, the 10 yoke being then bound in place by screws or otherwise. As is usual, a firing pin is carried by the breech block having a notched disk 10 through rotation of which the pin may be adjusted along its longitudinal axis 15 and locked in such adjusted position by means of a latch 11 which is adapted to selectively enter the notches.

Associated with the gun is a rammer 12, (see Figs. 4, 5 and 10), the rod of which 20 is housed in a casing 13 rigid on the cradle. The preferred form of rod herein shown is hollow and has a coiled spring 14 housed therein which is compressed upon rearward movement of the rammer between a screw 25 plug 15 which closes the end of the rod and a stop 16 which is secured to the cradle and extends within the rod through a slot 17 (see Figs. 1, 7 and 10) formed longitudinally thereof. The spring is held in compressed position by a spring actuated plunger 18 (see Fig. 29) which is housed in a recess in the rammer and is extended to engage the rear edge of the casing when the rammer is in its rearmost position. The 30 rammer is formed with an angled or U-shape head 19 providing a rammer finger 19' (Fig. 10) which is normally held in elevated position but which is automatically turned to ramming position by a lug 20 (see 35 Figs. 4 and 5) secured to the gun and projecting into a cam groove 21 formed in the rammer. As will be evident the rammer may be drawn to its rearmost position manually by grasping the head thereof or is moved to 40 such position by recoil of the gun.

For the purpose of operating the gun by hand a slide 22 (Figs. 4, 5, 23, 24 and 25) is mounted, preferably on the outer face of the left hand side of the cradle, to reciprocate in a T-groove provided in such side plate. The slide is formed with a grip 23 in which is mounted a spring retracted plunger 24 which engages a latch 25 adapted to normally rest in notches 26 to hold 45 the slide in forward or rearmost position and which is released by forcing the plunger inwardly. The slide is formed with a cam or inclined surface 27 which engages one arm of a bell crank lever 28 (Figs. 2 and 50 11) pivoted to the cradle and swung, when the slide is drawn rearwardly, so that its other arm forces forwardly a striker rod extension 29 (Figs. 2, 10 and 11) which projects through a slot 30 formed in the side 55 of the cradle and which is secured to the

striker rod 31 mounted for reciprocation within the cradle.

Striker rod 31 has a reduced portion 32 which is housed in a casing 33, rigid on the cradle, in which casing is a resilient element, such as the coil spring 34, which surrounds the reduced portion and is compressed by the forward movement of the rod.

The rear end of the rod is formed with a shoulder 35, adapted to contact the end 36 of a hammer which is pivotally mounted on a bracket 37 secured to the left side of the gun at the breech thereof, and also with a lug 38 spaced from the shoulder and adapted to engage the rib 36' (Figs. 16 and 17) 80 of the hammer when the rod moves forwardly to swing the hammer to cocked position in which position the rib 36' may pass the lug 38, as is necessary during recoil of the gun.

The hammer is formed with a head 39 which is adapted to swing through an arc of 90° to engage the firing pin. The hammer, when swung to cocked position is held by a sear 40 which is pivotally mounted on the left hand side of the gun and which is urged by a sear spring 40' into engagement with a lug 39' of the hammer. The sear is adapted to be tripped by the trigger to release the hammer.

When the slide 22 is drawn rearwardly a lever 41 pivoted at the left side of the gun cradle is rocked through its connection with the slide, which is herein shown as a stud 42 on the slide working in a T groove in the lever. The lever 41 is formed with a nose 43 which engages a shoulder on a cam 44 secured on the projecting end of a shaft 45 which is journaled in the side of the cradle and which has rigidly mounted on its inner end a latch plate 46 (Figs. 7, 8 and 9). Rocking of the lever will therefore rock the shaft and latch plate against a resiliently held plunger 47 which presses upon a toe 48 of the latch plate and tends to retain the plate in normal position.

The latch plate normally engages the lower edge of a slide 49 which works vertically in a groove formed in the side wall of the cradle and which is also supported by the left hand arm of the breech block yoke, which arm is in turn held in its raised position by a lug 50 on the latch plate which normally underlies the arm.

When the latch plate has been rocked to free the slide and arm as just described, a cam 51 rigid on the pivot shaft of the lever 41 engages a lug 52 (see also Figs. 4 and 5), projecting from a crank 53, which crank is pivotally mounted on an arm 54 depending from the gun, to rock such crank. When the crank is rocked a stud 55 thereon which engages in a groove formed in the breech block yoke causes the breech block to move downwardly to open position. The crank is 123

connected through a link 56 with a piston rod 57 working in a housing 58 in which is a resilient element, such as the coil spring 59, which is compressed upon rocking of the 5 crank to breech opening position and stores up energy for closing the breech. The breech is, however, prevented from closing during loading by a suitable latch herein shown as a spring actuated latch 60 which 10 is secured to the gun and which engages a breech block stop 61 carried by the block. This latch is released by an angle lug 62 on the rammer coming into contact with a pin 63 on the latch and so retracting the latch to 15 free the block as the rammer moves forwardly to ram a charge into the breech of the gun.

To provide for feeding a series of rounds to the gun and placing the rounds successively in position to be rammed into the gun, I prefer to mount upon the cradle a magazine of any desired form, a preferred form of such magazine being herein shown, in which trunnions 64' are provided on the cradle on 20 which the magazine 64 is pivotally mounted so that it may be swung forwardly when charging the magazine. The magazine is held in normal position by plungers 65, 65' (Figs. 26, 27 and 28) which are housed 25 therein and move transversely thereof and which are forced outwardly by springs to enter cups 66—66 positioned in lugs formed on the cradle. Pins 67—67 are carried by the respective plungers and extend through 30 slots formed in the magazine and may be grasped between the thumb and forefinger and drawn toward each other to release the plungers from the cups and free the magazine to swing upon the trunnions.

40 One of the plungers, herein shown as the right hand plunger 65' is formed with an extension thereon carrying a pin or projection 68 which takes into an aperture formed in the lower portion of a cartridge strip 69 which is positioned in the magazine, thus holding the cartridge strip in place. Pivotally mounted at the bottom of the cartridge strip is a latch 70, spring actuated to underlie the cartridges in the strip and retain them in place when the magazine is unlocked and swung from normal position, and rocked to free the cartridges, when the magazine is in normal position, by suitable means such as the plate 71 which is secured 50 to the cradle in position for its end to engage the latch and rock it against the tension of the spring.

Cartridges are forced from the magazine by suitable means such as the lazy tongs 72 60 forced toward extended position by a spring 73 housed in the side of the magazine. The lazy tongs is preferably provided with a shoe 74 which rests upon the topmost cartridge.

65 From the magazine the cartridges are fed

successively into a tray 75 which is mounted in the cradle on arms 77, 77' which are pivoted to the sides of the cradle. The tray is provided at its rear end with a latch 78 which engages, when the tray is in its up 70 position, the head of a latch bolt 79, secured in the cradle to hold the tray elevated but which is disengaged by a cartridge falling into the tray from the magazine to free the tray. When the latch is freed the tray is 75 still held in its up position by the actuating slide heretofore described which is in turn held by the latch plate 46 and left hand arm of the breech block yoke.

During hand operation of the gun, when 80 the slide 22 is drawn rearwardly, the latch plate is rocked from the actuating slide and the breech block forced downwardly to open the breech. The actuating slide and tray are then free to drop being forced downwardly by the spring 80 housed in a casing 81 rigid on the cradle and working against a hollow plunger 82 which actuates, through links 83, the feed tray arms. One of the feed tray arms, in this instance shown as the 85 rear left hand tray arm, is rigid on a pivot 84 which is journaled in and extends through the side of the cradle and carries on its outer end a cam 85 which, when the arm rocks toward tray lowering position, swings into the 90 path of the slide 22 and is engaged by the slide in its rearward travel and rides up the cam surface 86 of the slide thereby forcing the tray back to up position thus jogging the tray sufficiently to insure proper positioning of the cartridge therein and clearing any jams. When the slide is again thrust forwardly the tray drops since the latch plate is prevented from swinging back to 95 normal position by the arm of the breech 100 yoke engaging a lug 87 projecting therefrom as seen most clearly in Fig. 6.

As the feed tray drops downwardly to feeding position, lugs 87 extending from the rear arms contact the surfaces 88—88 of 105 dogs 89—89 which are pivoted on the cradle and which are thus swung inwardly, being also aided in such movement by the coil springs 90, to engage the cartridge next 110 above the one in the tray and so prevent a double feed. The cartridge is held securely positioned in the tray by means of the retaining leaves 91—91 which are pivotally mounted at each side of the tray and which are pressed upwardly by the spring pressed 115 plungers 92—92 so that they will rock to allow a cartridge to pass into the tray and will then spring back to normal position to overlie the cartridge and prevent it from being accidentally displaced from the tray. Provision is also made for holding the cartridge against longitudinal movement within the tray, and for this purpose I provide a cartridge retaining finger 93 connected to 120 the right hand feed tray arm having an 1

angled end 94 which engages over the rim of the cartridge when the tray is in up position and prevents the cartridge from sliding forwardly as might occur when the gun is pointed downwardly or upon recoil of the gun.

The cartridge retaining finger has an angularly disposed portion 95 thereon which, when the tray is swung downwardly, engages the rear of the cartridge and pushes it forward a short distance as the angled end of the finger disengages from the rim of the cartridge.

When the tray reaches its lowermost position a lug 96 projecting from the rear right hand feed tray arm engages the spring pressed plunger 18 which has been holding the rammer in its rearmost position and forces the plunger inwardly so as to release the rammer. The rammer then moves forwardly under impulse of its spring 14 and forces the cartridge into the cartridge chamber. When the rammer has reached the limit of its forward movement the angled face of a lug 62 formed on the rammer head engages the pin 63 of the latch thereby retracting the latch and freeing the breech block.

The breech block, being free from the latch, is immediately drawn to its up or closed position by the spring acting through link 54 upon the crank 53 through the rocking of which crank the breech block is raised in a manner similar to that described hereinbefore for the lowering of the block. In rising, the left hand arm 7 carries with it the actuating slide and tray thereby restoring the tray to normal position, during which restoration of the tray the lugs 87 engage the faces 97 of the dogs and swing them to position to release the next cartridge from the magazine and allow it to drop into the tray. During the upward movement of the breech block the rammer is raised to elevated position by reason of the fact that the ramming finger of the rammer head is extending within the U of the block and is carried up with the block. During this up movement the rammer is drawn slightly rearwardly by passing up the inclined face 98 of a projection 99 which extends from the breech of the gun and is held in such up position by engagement of said projection with a lug 100 formed on the rammer.

To fire the gun the grip 101 is grasped and the safety plunger 102 is forced inwardly by the grip of the hand thereon thus freeing the trigger 103 which is then pulled rearwardly. This safety plunger may be of any well known type as the same forms no part of the present invention. The trigger is connected through a rod 104 (Fig. 2) to the trigger mechanism 105, which mechanism is in the form of a lever pivotally mounted at the side of the gun and which has extending

therefrom substantially at right angles thereto, a collapsible plunger 106, (Fig. 5), which projects through a slot formed in the side plate of the gun. The end of this plunger is angled off so that the collapsible portion will be forced back, or to the left (Fig. 5) to permit the sear to pass on counter recoil, but will move outwardly under the action of its spring, not shown, to underlie the sear when the hammer is in cocked position. Since this plunger extends from the forwardly extending arm of the trigger mechanism 105 (Fig. 2) it swings upwardly as the lever 105 moves rearwardly thereby releasing the sear. Associated with the trigger mechanism is a half cock 107 which is pivotally mounted at the side of the cradle and which is swung when the trigger mechanism is pulled rearwardly so that its extension 108 is swung downwardly to allow the striker rod extension 29 to pass the same. The half cock normally lies in a position to engage a notch 118 formed in the striker rod extension.

The rearward swinging of the trigger mechanism trips the sear thereby freeing the hammer and striker rod so that the striker rod moves rearwardly under the force of its spring swinging the hammer through an arc of 90° to impinge upon the firing pin and prime the round.

When a round is discharged, as just described, the gun recoils within the cradle and the arms 7 of the breech block come in contact with the cam surfaces 109, provided on the sides of the cradle, which forces the breech block to lowermost or open position. When the arms have reached the position 110 in recoil the block is completely open, and extraction takes place due to the shoulders 111 of the breech block engaging the arms 112 of the extractors which are pivotally mounted on the gun and which have, on their other arms, extractor lips 113 which engage the rim of the cartridge or round and draw the cartridge from the cartridge chamber as the breech block is opened. After extraction a slight further recoil of the gun is had which permits the extractors to house themselves in recesses 114 formed on the breech of the gun so that the extractor lips will be out of the way and not liable to injury from being struck by the rim of the cartridge and also so as to permit the tray to come down flush with the rear of the cartridge chamber.

During this recoil of the gun the rammer has been carried rearwardly with the gun a sufficient distance to allow its retaining plunger to pass beyond the rammer casing and to engage the rear end of the casing to hold the rammer in such rearward position. The rammer during this rearward motion has been held in up position by reason of the fact that its lug has been in engage-

ment with the projection 99 of the gun so that the rammer could not interfere with extraction of the cartridge. During recoil of the gun the hammer has also been drawn to 5 cocked position by reason of the fact that the striker rod has only a very short travel rearwardly and the engagement of the striker rod lug 38 with the rib 36' of the hammer will necessarily cause the hammer to swing 10 upon its pivot until it has reached cocked position in which position the lug is allowed to pass the rib.

Upon counter-recoil the rammer is turned to its down or ramming position by means 15 of the angled lug 20 engaging in the cam groove 21 of the rammer and the left hand arm of the breech block yoke comes in contact with the lug 50' of the latch plate 46 thereby rocking the latch plate to release the 20 actuating slide and allow the feed tray to again drop as heretofore described to position a cartridge to be forced into the cartridge chamber upon forward movement of the rammer, which movement takes place by 25 reason of release of the rammer by the tray as heretofore set forth.

I claim:

1. The combination of a cradle, a gun 30 therein, a rammer and a rammer spring carried by the cradle, the rammer recoiling with the gun and the spring compressed thereby, means for locking the rammer in cocked position during recoil of the gun, the rammer normally in position clear of an extracted cartridge, means for retaining the rammer in such position during recoil, a sliding breech block carried by the gun, cooperating means on the block and cradle for opening the breech block during recoil, 35 means for locking the breech block in open position, a loading tray carried by the cradle, a magazine on the cradle for feeding rounds to the tray, means for locking the tray in round receiving position unlocked by delivery of a round to the tray, means for retaining the round in position in the tray releasing the round when the tray moves to loading position and urging the round toward the chamber, means associated with the gun 40 and cooperating with the rammer for automatically moving the rammer to ramming position during relative movement of the gun and rammer, means associated with the tray for automatically releasing the rammer 45 when the tray has reached loading position, means carried by the rammer for releasing the breech block locking means when the rammer has reached the limit of its forward movement, means for holding the tray in elevated position after unlocking of the tray locking means cooperating with means on the block on counter recoil to free the tray to move toward loading position, means associated with the magazine actuated by movement of the tray toward loading position to

retain rounds in the magazine and by movement thereof in the reverse direction to feed a round into the tray, the block and tray holding means cooperating to restore the tray to normal position, the breech block 70 and rammer cooperating to restore the rammer to normal position and manually operable means for moving the tray to free jams therein.

2. The combination of a cradle, a gun 75 therein, a rammer and a rammer spring carried by the cradle, the rammer recoiling with the gun and the spring compressed thereby, means for locking the rammer in cocked position during recoil, the rammer normally in position clear of an extracted cartridge, means for retaining the rammer in such position during recoil of the gun, a sliding breech block on the gun, cooperating 80 means carried by the breech block and the cradle for opening the breech block during recoil, means for locking the breech block in open position, means associated with the gun and engaging the rammer for automatically 85 moving the rammer to ramming position during relative movement of the gun and rammer, means carried by the rammer for releasing the breech block locking means when the rammer has reached the limit of its forward movement, the breech block and 90 rammer cooperating to restore the rammer to normal position, a loading tray and means carried by the tray for automatically releasing the rammer when a round has been brought in line with the gun. 100

3. The combination of a cradle, a gun 105 therein, a rammer and a rammer spring carried by the cradle, the rammer recoiling with the gun and the spring compressed thereby, means for locking the rammer in cocked position during recoil, the rammer normally in position clear of an extracted cartridge, means for holding the rammer in such position during recoil, a sliding breech block carried by the gun, means for automatically opening the breech block during recoil, means for locking the breech block in open position, means associated with the gun for turning the rammer to ramming position 110 during relative movement of the gun and rammer, means carried by the cradle for automatically placing a round in line with the gun, including means for releasing the rammer, means carried by the rammer for unlocking the breech block when the rammer has reached the limit of its forward movement, the rammer and block cooperating to rock the rammer to normal position. 115

4. The combination of a cradle, a gun 120 therein, a rammer and a rammer spring carried by the cradle, the rammer recoiling with the gun and the spring compressed thereby, means for locking the rammer in cocked position during recoil, the rammer normally in position clear of an extracted 125 cartridge.

- cartridge, means for holding the rammer in such position during recoil of the gun, means associated with the gun for rocking the rammer to ramming position during relative movement of the gun and rammer, and a feeding mechanism carried by the cradle including means for automatically releasing the rammer when a round has been placed in line with the gun.
- 5 5. The combination of a cradle, a gun therein, a rammer and a rammer spring carried by the cradle, the rammer recoiling with the gun and the spring compressed thereby, means for locking the rammer in cocked position during recoil, the rammer normally in position to clear an extracted cartridge, means carried by the gun for holding the rammer in such position during recoil, means associated with the gun for rocking the rammer to ramming position during relative movement of the gun and rammer, and means connected to the cradle for automatically releasing the rammer when a round has been placed in line with the gun.
- 10 6. The combination of a cradle, a gun therein, a rammer and a rammer spring carried by the cradle, the rammer recoiling with the gun and the spring compressed thereby, means for locking the rammer in cocked position during recoil, the rammer normally in position to clear an extracted cartridge, means for holding the rammer in such position during recoil, and means associated with the gun for rocking the rammer to ramming position during relative movement of the gun and rammer.
- 15 7. The combination of a cradle, a gun therein, a rammer and a rammer spring carried by the cradle, the rammer recoiling with the gun and the spring compressed thereby, a sliding breech block cooperating with the rammer to move the rammer to a position clear of an extracted cartridge, means for retaining the rammer in such position during recoil of the gun, means for locking the rammer in cocked position during recoil, means associated with the gun for moving the rammer to cartridge engaging position during relative movement of the gun and rammer and means for automatically releasing the rammer when a round has been brought to position in line with the gun.
- 20 8. The combination of a cradle, a gun therein, a rammer and rammer spring carried by the cradle, the rammer recoiling with the gun and the spring compressed thereby, means whereby when the gun has traveled through its recoil the rammer is held in cocked position, means for normally retaining the rammer in elevated position, cooperating means on the gun and rammer for rocking the rammer to ramming position during relative movement of the gun and rammer and a loading tray attached to the cradle including means whereby the rammer is automatically released when the tray has brought a round in line with the gun.
- 25 9. The combination of a cradle, a gun therein, a rammer and rammer spring carried by the cradle, means for normally retaining the rammer in elevated position out of line with the axis of the gun, and cooperating means on the gun and rammer for 75 rocking the rammer to ramming position during relative movement of the gun and rammer.
- 30 10. The combination of a cradle, a gun therein, a rammer and a rammer spring carried by the cradle, the rammer adapted to recoil with the gun and the spring compressed thereby, means operating on rearward movement of the rammer to lock the rammer in cocked position, the rammer normally held in elevated position, and means carried by the gun for rocking the rammer to lower position during relative movement of the gun and rammer.
- 35 11. The combination of a cradle, a gun therein, a rammer and rammer spring carried by the cradle, the spring compressed by rearward movement of the rammer, the rammer normally held in elevated position and cooperating means on the gun and rammer for 80 95 rocking the rammer to lower position during relative movement of the gun and rammer.
- 40 12. The combination of a cradle, a gun therein, a sliding breech block carried by the gun, cooperating means on the block and cradle for opening the breech block during recoil, a loading tray carried by the cradle, a magazine on the cradle for feeding rounds to the tray, means for locking the tray in round receiving position unlocked by delivery of a round to the tray, means for retaining the round in position in the tray releasing the round when the tray moves to loading position and urging the round toward the chamber, means for holding the tray in 100 105 normal position after unlocking of the tray locking means cooperating, on counter recoil, with means on the block to free the tray to move toward loading position, means associated with the magazine actuated by movement of the tray toward loading position to retain rounds in the magazine and by movement thereof in reverse direction to feed a round into the tray, the block and tray holding means cooperating to restore the tray to normal position, a resiliently actuated member released by movement of the tray to loading position to move a cartridge from the tray into the cartridge chamber and manually operable means for moving the tray 110 115 to free jams therein.
- 45 13. The combination of a cradle, a gun therein, a sliding breech block carried by the gun, cooperating means on the block and cradle for opening the breech block during 120 125 130

- recoil, a loading tray carried by the cradle, a magazine on the cradle for feeding rounds to the tray, means for locking the tray in round receiving position unlocked by delivery of a round to the tray, means for holding the tray in round receiving position after unlocking of the tray locking means cooperating, on counter recoil, with means on the block to free the tray to move toward loading position, means associated with the magazine actuated by movement of the tray toward loading position to retain rounds in the magazine and by movement thereof in the reverse direction to feed a round into the tray, the block and tray holding means cooperating to restore the tray to normal position, and manually operable means for moving the tray to relieve jams therein. 14. The combination of a cradle, a gun therein, a sliding breech block carried by the gun, cooperating means on the block and cradle for opening the breech block during recoil, a loading tray carried by the cradle, means actuated by movement of the tray for feeding successive rounds to the tray, means for locking the tray in round receiving position unlocked by delivery of a round to the tray, means for holding the tray in round receiving position after unlocking of the tray locking means, cooperating, on counter recoil, with means on the block to free the tray to move toward loading position, the block and tray holding means cooperating to restore the tray to normal position after the tray is freed of its round and manually operable means for moving the tray to relieve jams therein. 15. The combination of a cradle, a gun therein, a sliding breech block carried by the gun, cooperating means on the block and cradle for opening the breech during recoil, a loading tray carried by the cradle, means actuated by movement of the tray for feeding successive rounds to the tray, means for locking the tray in round receiving position, unlocked by delivery of a round to the tray, and means for holding the tray in round receiving position after unlocking of the tray locking means cooperating, on counter recoil, with means on the block to free the tray to move toward loading position, the block and tray holding means cooperating to restore the tray to normal position after the tray has been freed of its round. 16. The combination of a cradle, a gun therein, a sliding breech block carried by the gun, cooperating means on the block and cradle for opening the block during recoil, a loading tray carried by the cradle, means for feeding successive rounds to the tray, means for locking the tray in round receiving position unlocked by delivery of a round to the tray and means for holding the tray in round receiving position after unlocking of the tray locking means actuated, on counter recoil, to release the tray. 17. The combination of a cradle, a gun therein, a sliding breech block carried by the gun, cooperating means on the block and cradle for opening the block during recoil, a loading tray carried by the cradle and means for holding the tray in round receiving position during recoil actuated by means on the block, during counter recoil, to free the tray to move toward loading position. 18. The combination of a cradle, a gun therein, a breech block for the gun, a loading tray carried by the cradle, means for holding the tray in round receiving position during opening of the block, and means carried by the breech block for releasing the tray holding means on counter recoil of the gun. 19. The combination of a cradle, a gun therein, a loading tray carried by the cradle, mechanism actuated by movement of the gun for automatically operating the tray and manually operable means for operating the tray, such means causing the tray to move toward loading position and return to normal position. 20. The combination of a cradle, a gun therein, a loading tray carried by the cradle, mechanism for automatically operating the tray and manually operable means for unlatching the tray and causing a preliminary rocking movement thereof before allowing the tray to be lowered to round receiving position. 21. A cradle, a gun mounted to recoil and counter recoil freely therein, a breech block for the gun, a link motion controlled feed mechanism actuated by the breech block on counter recoil to position a round in rear of the breech of the gun and in line with the axis of the bore at the end of counter recoil, and means energized by the gun released by the feed mechanism to force the round from the feed mechanism into the cartridge chamber. 22. A cradle, a gun mounted to recoil and counter recoil freely therein, a breech block for the gun, a feed mechanism actuated by the breech block on counter recoil to position a round in rear of the breech of the gun and in line with the axis of the bore at the end of counter recoil and means energized by the gun released by the feed mechanism to force the round from the feed mechanism into the cartridge chamber. 23. A cradle, a gun mounted to recoil and counter recoil freely therein, a breech block for the gun, feed mechanism actuated by the breech block on counter recoil to position a round to be fed into the gun and means energized and positioned by the gun on recoil and counter recoil and released by the feed mechanism to force the round from the feed mechanism into the cartridge chamber.

24. A cradle, a gun mounted to recoil and counter recoil therein, a breech block for said gun, means for opening the breech block, a feed mechanism actuated by the breech block 5 when open to position a round to be fed into the gun, means released by the feed mechanism to force the round from the feed mechanism into the cartridge chamber, means released by said last mentioned means for closing the breech block and restoring the feed mechanism to normal position.
25. A cradle, a gun reciprocable thereon, a breech block, means for opening the block, feed mechanism actuated by the block when 15 open to position a round to be fed into the gun and restored to normal position by the block in closing.
26. A cradle, a gun reciprocable thereon, a rammer normally held by the gun clear of 20 the bore and adapted to be energized by the gun on recoil for independent return to battery, means operable on counter-recoil for moving the rammer to loading position, a breech block, means for opening the block 25 and locking it in open position, said locking means rendered inoperative by the rammer on arriving in battery, and said block in closing adapted to restore the rammer to initial position.
27. A cradle, a gun reciprocable thereon, a rammer adapted to be energized by the 30 gun on recoil for independent return to bat- tery, a breech block, means for opening the block and locking it in open position, said locking means rendered inoperative by the rammer on arriving in battery.
28. In an automatic gun, a breech block, a feed tray normally in round receiving position and movable into and out of loading position, and manually operable means for 40 simultaneously opening the block with the gun in battery and moving the tray through a half cycle.
29. In an automatic gun, a breech block, a feed tray movable into and out of loading 45 position, and manually operable means for simultaneously opening the block with the gun in battery and moving the tray through a half cycle.
30. In an automatic gun, a breech block, a feed tray movable into and out of loading position and manually retractable means for simultaneously opening the block with the gun in battery and rocking the tray, said means when restored to initial position permitting the tray to move to loading position.
31. A cradle, a gun reciprocable thereon, a breech block, a firing mechanism therein, a hammer for said mechanism and manually operable means carried by the cradle for simultaneously opening the block with the gun in battery and cocking the hammer.

THOMAS M. JERVEY.
